UNITED STATES PATENT OFFICE.

GEORGE H. MINIER, OF SOUTH PASADENA, CALIFORNIA.

DESIGN FOR A GAS-HEATER CASING.

45,947.

Specification for Design.

Patented June 16, 1914.

Application filed April 22, 1914. Serial No. 833,814. Term of patent 14 years.

To all whom it may concern:

Be it known that I, GEORGE H. MINIER, a citizen of the United States, residing at South Pasadena, in the county of Los Angeles and State of California, have invented a new, original, and ornamental Design for a Gas-Heater Casing, of which the following is a specification, reference being had therein to the accompanying drawing, forming part thereof.

Figure 1 is a perspective view of a gas heater casing showing my new design. Fig.

2 is an end elevation of a heater casing illustrating my new design.

I claim:

The ornamental design for a gas heater casing as shown.

In testimony whereof I hereunto affix my signature in presence of two witnesses.

GEORGE H. MINIER.

Witnesses:

E. E. WASHBURN,
L. L. WASHBURN.
